UNITED STATES PATENT OFFICE.

PAUL M. LINCOLN, OF PITTSBURGH, PENNSYLVANIA.

AMMETER.

1,248,511.

Specification of Letters Patent.

Patented Dec. 4, 1917.

Application filed May 16, 1914. Serial No. 839,051.

To all whom it may concern:

Be it known that I, PAUL M. LINCOLN, a citizen of the United States, residing at Pittsburgh, in the State of Pennsylvania, have invented certain new and useful Improvements in Ammeters, of which the following is a specification.

My invention relates particularly to instruments for measuring electric current and is primarily designed to provide a sensitive and accurate current meter; in addition to which I provide means for making the response or indication slow so that at any instant the indication is due to the average current that has passed for a certain given time. For this reason the device may serve as a maximum demand meter also. In the construction I employ the principle of the heating effect of current traversing a conductor, and by using two duplicate members as described, I compensate for errors that might occur from change of temperature of the air. The invention is illustrated in a preferred form in the accompanying drawings wherein—

Figure 1 is an elevation from the front of the inside mechanism, certain parts being removed; Fig. 2 is an outside face view from the same direction, showing the dial pointers; Fig. 3 is a central vertical section of the casing of the instrument, a partial side elevation of the inside mechanism being shown at right angles to the view of Fig. 1 and from the right; Fig. 4 is a partial bottom view of the casing showing the opening for setting the pointers and Fig. 5 is a cross-section of the actuating curved tubes.

Referring first to Fig. 1, I provide a pair of expansion tubes 6 and 7, identically alike, bent in the form shown, and being of cross-section as shown in Fig. 5 and filled with a highly expansible liquid such as oil or mercury or xylene or toluene. The bent tube 6 is delicately and fixedly pivoted at 8, to a stud in the casing and its upper end is free to move except that its end is attached by a pivot 9 to the upper end of the duplicate tube 7 and to one end of a link bar 10 pivoted at 11. The tube 7 at its lower end is likewise pivoted to a link bar 12, pivoted at 13, and also carries a link 14 which at its top is pivoted to a rocking gear sector 15 pivoted at 8 on the fixed stud, carrying the lower end of tube 6.

The electric current to be measured is led from the binding post 16 by flexible leads 17 and 18, through the expansible tube 7, as shown, back to the other binding post 19. It will be evident that the passage of the current through or around the tube 7 will heat it, cause the fluid therein to expand and therefore tend to straighten out the bent tube. By reason of the control of the links 10 and 12, and the attachment of the upper end of tube 7 to the tube 6, it is evident that the pivot point 14^a at the lower end of the tube 7 will move virtually in a vertical direction, thereby rotating the sector 15 by the link 14.

Evidently any changes of temperature in the tubes 7 and 6, which are common to both, will have no effect in moving the sector 15, since an equal and simultaneous expansion or contraction of both tubes 7 and 6 will have no other effect than to cause a vertical movement of the pivot 9, unopposed. The tube 7, when made of metal may serve as a path for the current, or otherwise it might be insulated and a wire wound over its outside.

Referring more particularly to Fig. 3, the pivoted sector 15 has its teeth engaged with a gear pinion 20 fixed on the shaft 21 of the indicating pointer 22, which travels over a proper scale on the dial plate 23. I provide a spiral spring 24, (Fig. 1) to keep the back-lash of gears, pivots, links, etc., always in the same direction while the zero position of the pointer is adjusted by adjustment of the links 10 and 12 which are pivoted respectively at 11 and 13, on upturned lugs of the spring support 25 fixed at its middle on post 26, and adjustable in position by adjusting screws 27 and 27^a.

In order to use the instrument as a maximum demand meter, I provide, in addition to the pointer 22 directly moved by the expansion of the tube 7, a second pointer 28 (Figs. 2 and 3), which is attached to a tube 29 loosely surrounding the pointer shaft 21. The pointer 28 is provided with a light friction by means of a spring washer 30, so that it will remain at the highest point to which it has been pushed by engagement with pointer 22 in the usual way. In order to reset this maximum demand pointer 28, I provide the tube 29 with a bevel gear 31 to be engaged by another bevel gear 32 on the

key shaft 33 and normally held out of mesh by spiral spring 34. The key shaft 33 is reached through a small door 35 in the bottom of the casing as shown in Fig. 4, and to prevent unauthorized tampering I provide a studded hasp 36 passing through a slot in the door 35, so that a padlock can be used.

Both the pointers are counterbalanced so as to be supported at the center of gravity, which prevents the pointer 28 especially from creeping under the influence of vibration.

The change of distance between the ends 15 of tube 7 can be made directly proportional to the temperature change, and it being understood that the heat produced by the current through the tube is proportional to the square of the current, I make the movement 20 of the pointer 22 more nearly proportional to the current instead of the square of the current, by use of the link motion and proportions as shown. Preferably the pivot 14^a should have a motion such that the sector 15 is caused to turn through an angle 25 of about 90°. Evidently motion at and near the no load position will cause a considerably greater motion of the pointer than the same amount of movement would do at or near full load condition. This effect is obtained 30 by the use of the sector 15 and the link 12, so that the scale divisions on the dial may be made more even.

It will thus be seen that in my device the 35 ammeter pointer will not move with any change of temperature, except that due to the passage of current through the tube 7 and that the full movement of the pointer will not take place until some time has elapsed, so that the position at any time will 40 indicate the average current that has passed for a given previous length of time. The response may obviously be made slower by changing the liquid therein, by loading the 45 tubes with extra weight, as by wire windings 7^a or making them of greater dimensions.

The time of response follows a logarithmic 50 curve; that is, if a given load is thrown on the instrument, the indication approaches its final value along a logarithmic curve with respect to time. The time to reach a given proportion of its final value will depend upon the relation of the radiating surface of the tube 7 to its heat storage capacity. By 55 changing either of these quantities, the time of response may be modified.

The instrument is adjustable in all parts and simple and accurate in construction, and I regard the principal advantages as resting 60 upon the use of the like pair of expansible bars arranged to indicate their relative expansion due solely to the passage of the current to be measured, together with the provision for adjusting and accurately determining the time lag, and use of the mecha-

nism shown for exaggerating the readings of the scale at low amperage position of the pointer.

Having thus described my invention and its use, I claim the following:

1. A measuring instrument comprising two fluid-containing similar expansion members pivoted together at one of their ends, one end of one of the members being pivoted to a stationary member, a pointer connected to the free end of the other member, and means for modifying the time of response of the pointer by varying the relation between the heat-storage capacity and the radiating ability of one of the members.

2. In an ammeter, the combination with a dial and a pointer, of two U-shape expansion elements of like construction pivoted together at one of their ends, the other end of one of said elements being fixedly pivoted and the other end of the other element being connected by gearing to the said pointer, one of the said elements being adapted to be heated by the current to be measured, and means for adjusting the time-lag between the passage of the heating current and the response of the indicator, substantially as described.

3. An ammeter comprising two fluid-containing hollow expansion tubes of substantially U-shape adapted to be pivoted together at one of their ends, one end of one of the tubes being pivoted to a stationary member, a pointer operatively connected to the free end of the other tube, and means for modifying the time-lag of the pointer by varying the relation between the heat-storage capacity and the radiating ability of one of the tubes.

4. An ammeter comprising two operatively connected expansion tubes one of which is pivoted at one of its ends to a stationary member, a pointer operatively connected to one end of one of the tubes, one of the said tubes being adapted to be heated in accordance with the current to be measured, and a plurality of adjustable pivoted links adapted to be attached to the ends of the said heated tube for varying the normal position of the pointer.

5. In an ammeter, the combination with a dial and pointer, of an expansible tube of liquid bent into general U-shape and having one end mounted on a fixed pivot, a second and like tube pivoted at one side to the first tube and at its other side provided with a link and gearing adapted to move the pointer, said second tube being also pivotally attached at both ends to the ends of links having fixed but adjustable pivots at their outer ends, substantially as described.

6. In an ammeter, the combination with a dial and pointer, of a bent expansion tube fixedly pivoted at one end, a second and exactly similar expansion tube having one end

5 pivoted to the free end of the first, and a gearing connecting the pointer with its other end, and adapted to produce relatively greater movement of the pointer in the vicinity of the no-load position of the pointer, said expansion tubes being provided with means for adjusting the relation between their heat absorbing and heat radiating capacities, substantially as described.

10 7. In a measuring instrument, the combination with a scale and a pointer, of a fluid-containing expansible tube of substantially U-shape having one of its ends mounted on a stationary pivot, a second similar tube adapted to be pivotally connected at one of its ends to the free end of the other tube, the other end of the said second tube being operatively connected to the pointer, and links the inner ends of which are pivotally attached to the respective ends of the second tube and the outer ends of which have fixed but adjustable pivots.

15 8. A measuring instrument comprising two fluid-containing oppositely disposed expansion tubes, one of which is fixedly pivoted at one of its ends, a pointer, means for operatively connecting the pointer to one end of the second tube, the remaining ends of the said tubes being pivotally connected together, one of the said tubes being adapted to be heated in accordance with the quantity to be measured, and a plurality of adjustable pivoted links adapted to be pivotally attached to the ends of the said second tube to vary the normal position of the pointer.

20 9. An ammeter comprising a pointer, two similar expansion members of substantially U-shape pivoted together at one of their ends, the other end of one of the members being pivoted to a stationary member and

the other end of the other member being operatively connected to the pointer, one of the said members being adapted to be heated in accordance with the current to be measured, and means for adjusting the time-lag between the passage of the heating current and the response of the pointer.

25 10. An ammeter comprising a pointer, two similar expansion members of substantially U-shape pivoted together at one of their ends, the other end of one of the members being pivoted to a stationary member and the other end of the other member being operatively connected to the pointer, one of the said members being adapted to be heated in accordance with the current to be measured, and means for so changing the relation between the radiating surface of one of the members to its heat storage capacity that the time-lag between the passage of the heating current and the response of the pointer may be any predetermined value.

30 11. An ammeter comprising two fluid-containing hollow expansion tubes of substantially U-shape adapted to be pivoted together at one of their ends, one end of one of the tubes being pivoted to a stationary member, a pointer operatively connected to the free end of the other tube, and means for modifying the time-lag of the pointer by varying the relation between the heat storage capacity and the radiating ability of the tube that is operatively connected to the pointer.

35 In testimony whereof I have hereunto signed my name in the presence of the two subscribed witnesses.
